UNITED STATES PATENT OFFICE.

MARCUS ORLEAN WHITEHORN, OF WORTHING, ENGLAND.

HOE.

No. 917,980.

Specification of Letters Patent. Patented April 13, 1909.

Application filed July 18, 1908. Serial No. 444,302.

To all whom it may concern:

Be it known that I, MARCUS ORLEAN WHITEHORN, a subject of the King of Great Britain and Ireland, residing at 45 Howard 5 street, Worthing, in the county of Sussex, England, have invented new and useful Improvements in Hoes, of which the following is a specification.

This invention relates to improvements in 10 hoes, the object being to provide a tool constructed in such a manner as to combine two forms of hoe namely, the straight hoe and a hoe with the blade at right angles, or approximately so, to the handle.

15 An implement of this nature possesses many advantages inasmuch as it obviates the necessity of carrying two separate tools from place to place furthermore, the cost of such a device is considerably below that of 20 two implements.

This invention consists essentially in pivoting the blade to the extremity of the handle or attachment thereto in such a manner that it may be secured in line with the said handle 25 or turned and secured approximately at right angles thereto and in order that the invention may be more fully understood, it will now be described with reference to the accompanying drawings, in which:—

30 Figure 1 is a front elevation of a hoe constructed according to this invention, and Fig. 2 is a side elevation thereof showing the blade in its second position in dotted lines.

In carrying this invention into practical 35 effect, and as shown in the drawings, the blade *a* is carried in the usual manner by arms *b* extending from a neck *c*. The neck *c* is reduced as at *c'* and pivoted as at *c''* between the forked extremity *d* of a rod *d'* designed 40 to be secured to and carried by a suitable handle. At one side of the rod *d'* is pivoted

as at *e* a trigger *e'* carrying a pin *f* pivoted thereto as at *f'* the pin *f*, in the normal position of the blade *a* as shown in Fig. 1 passing through holes or perforations in the rod *d'* 45 and the reduced neck *c'* firmly retaining them in position, a spring *g* carried by the trigger *e'* and bearing against the rod *d'* holding the said trigger in position and preventing the withdrawal of the pin *f*. 50

When it is desired to bring the blade into the position shown in dotted lines, in Fig. 2, the trigger *e'* is depressed thereby withdrawing the pin *f* from its holes or perforations whereupon the blade *a* can be turned until 55 the pin *f* reengages the holes or perforations in the rod *d* and bears against the edge of the reduced neck *c'* or enters a recess *h* formed therein when the said blade is held sufficiently firmly to enable it to be employed in 60 the well known manner.

Having now described my invention, what I claim as new and desire to secure by Letters Patent is:—

The combination, with a handle provided 65 with a forked end portion having a transverse passage through the branches thereof, of a blade provided with a shank which is pivoted in the said forked end portion and provided with an opening which registers 70 with the said passage, and a retractable locking-pin slidable in the said passage and arranged to bear against one side of the shank when the shank is placed at right angles to 75 the handle.

In testimony whereof I affix my signature in presence of two witnesses.

MARCUS ORLEAN WHITEHORN.
